ATTORNEY.

UNITED STATES PATENT OFFICE.

FREDERICK W. OLTERSDORF, OF DETROIT, MICHIGAN.

ROTARY SWING.

Application filed April 8, 1927. Serial No. 182,008.

This invention relates to improvements in rotary swings intended for use as amusement devices.

It is an object of the invention to provide 5 a rotary swing having accommodation for passengers which is supported by radial members rotatably arranged around a stationary centre post; and means so located with respect to the accommodation that 10 some, at least, of the passengers may supply the motive power by which the radial members are driven around their circular path.

Another object of the invention is to provide a rotary swing wherein the radial 15 members are held in spaced relation to one another, and wherein other accommodation for additional passengers is so arranged on said members that they are carried around by the motive power supplied by the working 20 passengers.

Having thus broadly outlined the major 25 purposes of the invention I will now describe one simple and practical embodiment of the invention with the help of the accompanying drawings, in which:

Figure 1 illustrates a plan view of the invention.

Figure 2 shows a side view of one radial member and the centre post, partly in section 30 and partly in elevation.

Figure 3 is an end view of one of the radial members showing a seat thereon.

Figure 4 is an enlarged view of the upper 35 end of the central post, showing the method of supporting the upper ends of the braces for the radial members.

Figures 5 and 6 are details showing a modified form of support for the stationary centre post.

40 Figure 7 shows a modified arrangement of the radial members with circular frames mounted thereon, this view being on a reduced scale.

45 Referring to the drawings, 1 designates a centre post supported in a substantially vertical position in any desired manner. For this purpose, when the installation is to be permanent, a sleeve 2 may be sunk in the ground to receive it; the line indicated at 50 3 in Figure 1 shows the ground level. For temporary installations a base 35 having radiating feet 36 may be employed. The lower end of the post in that case rests against the cut ends of the feet, and a collar 37 is secured around the post as by a pin 38. Attached to the collar are a plurality of radiat-

ing braces 39, the outer end of each of which latter is fastened as by a pin 40 to one of the feet.

Referring more particularly to Figures 1 to 4. Secured around the post 1 is a collar 4 the upper surface of which supports a central plate 5 over which latter a second collar 6, also fixed around the post, may be provided in order to hold the plate in position.

60 Radial members 7 and 8, arranged in pairs, are supported on the plate 5. In this construction it will be seen that the members 7 extend in both directions from the plate and rest thereon substantially centrally of their 70 length, whereas the members 8 project outwardly from the plate and are each less than half the length of the members 7. The exact number and arrangement of the radial members is however a matter of choice, and may 75 be varied to suit the style of swing. Each pair of radial members are transversely stiffened as by reinforcing members 9, 13 and 15, and secured to the latter in a depending position are bearings 10, 12 and 14.

80 Around the post 1, and under the collar 4 usually, a supporting plate 26 is secured, generally welded. On this supporting plate a crown gear 27 is fixed. Meshing with this gear are a plurality of bevel pinions 28, one 85 of which is fastened on the inner end of each of the shafts 11. These shafts, which are so arranged as to extend substantially radially one under each pair of radial members 7 and 8, are supported by the bearings 90 10, 12 and 14. Intermediately of their length, and usually between the bearings 10 and 12, these shafts are cranked as shown at 29.

95 On one of each pair of radial members 7 and 8, and towards their outer ends, supports 31 and 32 are secured to carry a seat 30. In the construction shown the device is intended to be operated by the riders' feet, so the seats should be so positioned as to be substantially centrally located over the 100 cranks 29. Other intermediate seats 33 may also be similarly arranged on the radial members, and in the present instance the shafts are not cranked thereunder; these latter seats are intended for smaller children 105 who are so placed that they will not travel as fast as the passengers in the seats 30. 34 indicates handles, one of which is arranged opposite each seat and is secured at its lower end to the radial member, 7 or 8, opposite 110 the one to which the supports 31 and 32 are secured. It will be noted that no fastening

means are shown between the central plate, the radial members, the reinforcing members, seat supports, seats, and handles since the connections are, in the present instance 5 welded, though when desired other means for fastening the parts to one another may be employed when desired.

In the upper end of the post 1, which is tubular, a pocket 16 is inserted which has a 10 flange 20 at its upper end that bears on the upper end of the post. Internally the pocket is circular and terminates at its lower end in a substantially semi-spherical concavity. The latter supports a ball 17 on which the lower 15 end of the spindle 18 rests. This spindle is rotatably supported by the circular wall of the pocket, has an intermediate portion 23 of reduced diameter, and terminates at its upper end in a threaded portion 23^a. The 20 shoulder 19 formed at the junction of the lower and intermediate portions of the spindle is located slightly above the top of the flange 20. Mounted on the intermediate portion and bearing on the said shoulder is a 25 rotary element 21 having radial projections 25 integral with it. The element is held in position by a nut 22, shown in the drawings of spherical design, in threaded engagement with the upper end 23^a of the spindle. 30 30 designates inclined braces attached at their upper ends to the projections 25 and at their lower ends to the radial members 7 or 8.

In Figure 7 it will be noted that from the central plate 5^a a plurality of radial members 7^a extend which support inner and outer 35 annular frame members 41. The said frame members support seats 30^a and also cross members 42 in the front of the seats. The

said cross members have the lower ends of the handles 34^a secured to them. Similar 40 shafts 11^a having cranks 29^a are arranged under the seats. The fragmentary view of this construction is shown in order to convey one of the many variations in construction to which the invention is susceptible. 45

Obviously the passengers in the seats 30, or 30^a, rotate the shafts 11 by turning the cranks 29, thereby causing the pinions 28 to travel around the crown gear 27.

While in the foregoing one embodiment of 50 the invention, and one slightly modified construction, has been described and shown, it is understood that other modifications and alterations may be made therein provided they fall within the scope of the appended 55 claim.

What I claim as my invention and desire to secure by Letters Patent is:

A rotary swing comprising a stationary 60 hollow centre post, a frame rotatably mounted around said post, a stationary gear secured around said post, cranked shafts rotatably mounted on said frame, pinions mounted on said shafts and meshing with said stationary gear so that when said cranks 65 are turned said pinions travel around said gear, a pocket in the upper end of said post, having a semi-spherical lower end, a ball in said pocket, a vertical spindle rotatable in said pocket and having its lower end resting on said ball, a rotary element around the upper end of said spindle above said post, and braces extending downwardly and outwardly from said element to said frame. 70

FREDERICK W. OLTERSDORF.
